UNITED STATES PATENT OFFICE

HARRY L. WOOD, OF LAKEWOOD, OHIO, ASSIGNOR TO DAVID W. K. PEACOCK, OF CLEVELAND, OHIO

WORK-FEEDING MECHANISM FOR TYPEWRITING MACHINES

Application filed September 2, 1925. Serial No. 54,000.

My invention relates to power transmitting devices for automatically operating mechanism for feeding work sheets to typewriting machines, and particularly to power transmitting devices for operating a feeding apparatus of the type embodying the general principles shown, described and claimed in U. S. Patent No. 1,481,489, issued to G. T. Trundle, Jr.

An object of the invention is to provide for automatic operation of apparatus and a typewriter platen to feed work sheets from a magazine into position with the platen for a typing operation and which will eject the preceding work sheet from the platen, such driving mechanism being self-releasing after each actuation when a complete operation of the apparatus has been performed.

These and other objects will appear more fully hereinafter.

The annexed drawings and the following description set forth in detail certain means embodying my invention, the disclosed means, however, constituting but one of the various forms in which the principle of the invention may be applied.

In said annexed drawings, Figure 1 is a front elevation of a device embodying my invention, shown in conjunction with a typewriting machine of a standard type and connected with the shafts for operating work sheet feeding mechanism shown and described in Patent No. 1,481,489 above referred to. Fig. 2 is a front fragmentary section of the mechanism for actuating the platen and finger feeding shafts, taken on line 2—2 of Fig. 3; Fig. 3 is vertical medial longitudinal section of the power transmitting mechanism; Fig. 4 is a sectional view taken on line 4—4 of Fig. 3 showing the reduction gearing and the self-releasing clutch; Fig. 5 is a sectional view taken on line 5—5 of Fig. 4 with a fragment of the reduction gearing casing broken away; Fig. 6 is a section of one of the clutch elements; Fig. 7 is a section of another clutch element; Fig. 8 is a section of the clutch elements assembled; Fig. 9 is a section of a clutch element taken on line 9—9 of Fig. 6; Fig. 10 is a sectional view of a clutch element taken on line 10—10 of Fig. 7; Fig. 11 is a sec-

tional view of the clutch elements assembled, taken on line 11—11 of Fig. 8; and Fig. 12 is an elevational view of the pin for associating the clutch elements.

Referring to the drawings by characters of reference, 1 represents a typewriting machine having a platen 2 carried by a shaft 3 having an end 4 projecting beyond the side of the machine. The typewriting machine is mounted upon the base 5 supported by the frame 6, and the primary work sheet feeding apparatus 7 is also mounted on the base and extends in a plane above the typewriting machine. The work sheet supply magazine and the primary feeding mechanism for moving the envelopes from the magazine to the platen are substantially the same as described in the above mentioned patent and reference may be had thereto for a description and illustration.

The typewriter is positioned upon the support below the lower end of the feeding apparatus, and so placed that work sheets which are discharged from the apparatus will be projected behind the platen 2 and in front of the pressure rollers, not shown, disposed to the rear of the platen 2. The operation of the primary feeding apparatus to bring a work sheet into the described position is referred to hereinafter as the primary feeding operation. After the work sheet has been so placed, the platen 2 is partially rotated whereby such work sheet is brought around said platen and into position to have the address typed upon it by the typewriter. This operation of the platen is hereinafter referred to as the secondary feeding operation.

Mechanism is provided for operating the rod 8 and the shaft 4 to actuate the primary and secondary feeding apparatus, and is driven by power actuated mechanism which is arranged to be connected by the operator and to be self-releasing so that only one complete work sheet feeding operation is performed upon each connection made by the operator.

Disposed to the right of and extending to the rear of the typewriter 1, and suitably secured to the base 5, is a plate 10 provided with a central guide portion 11. The guide and

70

75

80

85

90

95

100

the base are provided with longitudinally extending slots through which the bolt 12 extends and is secured by a nut 13. Mounted on the plate 10 is a standard 14 having a 5 groove 15, which fits over the guide portion 11. The bolt 12 extends through an aperture in the standard and slidably secures it in desired position on the plate 10, so that the standard may be adjusted transversely with 10 the axis of the platen 2. The right hand face of the standard 14 forms a vertical plane surface against which is seated a frame member 16, secured and vertically adjustable on said face by means of bolts 17.

15 The lower end of member 14 is provided with two laterally extending arms 19 upon the ends of which are formed bearings 20 in which is journalled a rock shaft 21. The power driving mechanism, hereinafter described, is 20 connected to operate this shaft 21 to cause it to actuate mechanism for operating the secondary feeding apparatus and to operate the primary feeding mechanism.

Intermediate the bearings 20, is a crank 25 arm 23, whose free end, 24, articulates with the lower arm 25 of an oscillatory gear segment 26 mounted upon a pivot 27 fixed to the frame 14. This segment 26 meshes with a 30 segmental pinion 28 which is loosely journalled upon a journal rod 29 mounted upon and fixed in the upper part of the frame member 16. This pinion 28 is formed with an extension 30 and a shaft 31 extends therefrom and has a pawl 32 fixed to the projecting end, 35 laterally of said pinion. The pawl 32 is provided at its free end with a pin 32' and a spring 34 is secured to the shaft 31 and bears against the pin 32'. Said pawl engages a ratchet wheel 33 mounted upon the hub of 40 and splined to a bevel gear 35 which is itself loosely journalled upon the journal rod 29. The gear 35 meshes with the bevel pinion 36 which is provided with an extended hub 37 journalled in a bearing 38. This bearing is 45 formed centrally of a yoke 39 which is provided with an end bearing 40 in which is mounted the journal rod 29.

The pinion 36 is formed with an axial cylindrical bore through which extends a 50 reciprocable rod 41, provided with a longitudinal groove 42 which is engaged by a spline 42 fixed upon the interior of the pinion 36. The rod 41, therefore, may reciprocate longitudinally through said pinion but is rotatively 55 fixed relative thereto. A sliding cross head 43 is mounted upon the rod 41, and the latter is provided at its right hand end with a fixed collar 44 which limits the movement of said cross head on the rod. Articulating with the 60 latter are two links 45, which also articulate with the upper end of a crank arm 46.

The left hand end of the rod 41 is connected with the shaft extension 4 of the platen shaft by means of a universal joint 47.

65 A pawl releasing segment 48 is rotatably

mounted upon the hub of the bevel gear 35 and is provided with an outer cam surface 49 with which the end of the pin 32' will engage during a portion of its movement when the pinion 28 is operated. A shaft 50 is mounted 70 longitudinally in a bearing 51 formed with one of the standards 14, and is provided with a knurled nut 52 exteriorly of the casing. The inner end of the shaft 50 has a pinion 53 secured thereto and meshes with teeth 54 formed on a portion of the periphery of the segment 48. By rotating the knurled end of the shaft 40 the segment can be rotated by means of the pinion 53 and the teeth 54 with which it engages to locate the cam portion of the periphery of the segment so that the pawl 32 will be released from the engagement with the gear 33 at any desired point to control the rotation of the typewriter platen while the mechanism continues to operate the full movement. 80

When the shaft 21 is rocked to the left the segment 26 will be moved to the right on its pivot 27 and will rotate the segment 28. The pawl 32 being held in engagement with the pinion 33 by the spring 34 will rotate the 90 pinion 33 with the segment 28. The ratchet 33 and the gear 35 being pinned together will cause rotation of the pinion 36 and the rod 41 which is slidably keyed therewith and the platen 3 is thereby rotated. The cam 95 surface of the segment 48 is positioned so that the pin at the free end of the pawl will ride thereon out of engagement with the pinion 33 after a desired driving movement, so that the driving connection just described 100 between the segment 28 and the pinion 33 can be disengaged in this manner. By adjusting the position of the cam, the rotation of the platen can be regulated to be driven the full 105 driving movement of the segment 28, or any lesser amount of rotation of the platen can be obtained while the segment continues a uniform driving movement.

A lever 60 is secured to one end of the shaft 21 and is pivotally connected to the lower end 110 of the rod 8 for operating the primary feeding device. A link 61 is pivoted to the lever 60 adjacent to the shaft 21. The link 61 is reciprocated to rock the shaft 21 and to reciprocate the rod 8 for operating the primary 115 feeding device, by proper transmitting mechanism hereinafter described.

The rod 8 moves with the link 61, and when moving downwardly the feeding device it 120 operates is returning from a feeding operation, while the secondary feeding device or rotation of the platen is in progress. When the link 61 moves upwardly the primary feeding device will be moving a work member to the platen, while the pawl will be idling 125 and will not operate the platen rotating mechanism. The rotation of the platen will eject the work member preceding the next work member moved thereover.

An electric motor 63 is secured to the frame 130

6 and drives a belt 64 which extends around the pulley 65. The pulley is keyed to a stub shaft 66 which is carried in a bearing 67 extending through a casing 68 secured to the end of an extension 69 projecting from and secured to the frame member 16. A pinion 70 is secured upon the enclosed end of the shaft 66 and meshes with an internal ring gear 71 which is secured to the shaft 72. The extension 69 is formed with a hollow hub portion 73 in which is carried a clutch, and one end of the shaft 72 extends into such clutch housing. The shaft 72 is supported in a bearing 74 in the extensions 69 and a bearing 75 in the casing 68. The pulley, pinion and ring gear provide speed reduction transmitting mechanism which can be continuously in operation during the operation of the machine.

20 A clutch element 76 is secured upon the end of the shaft 72 and cooperates with another clutch element 77 which is secured to a shaft 78, which is in axial alignment with the shaft 72 and extends through a bearing in 25 an end closure plate 79 removably secured to the open end of the clutch housing. An eccentric 80 is secured to the projecting end of the shaft 78 and the link 61 is pivotally secured at its upper end thereto. Rotation of 30 the shaft 78 will therefore reciprocate the link 61 and operate the primary and secondary feeding mechanisms above referred to and described.

The clutch element 76 is provided with an 35 annular recess 81 at one end into which a reduced portion 82 of the clutch element 78 extends. The clutch element 76 is provided with a plurality of annular apertures 83 which extend axially therewith and are arranged in a circle about the axis so that the portions thereof extending through the recessed portion will be semi-circular. The clutch element is provided with an aperture 84 adapted to be aligned with any one of the 40 apertures 83 in the clutch element 76, and the portion of the aperture 84 extending in the reduced portion of the element is semi-circular. A clutch pin 85 is provided with an annular portion which is mounted in the annular aperture 84 in the clutch element 77 and with a semi-circular end portion 86 which is mounted in the semi-circular portion of the aperture 84. An arm 87 extends from the outer end of the pin and a control member 88 45 is reciprocably mounted in the clutch casing so as to be moved into and out of position to engage the pin arm to rotate the pin. A bell crank 90 is pivoted to the casing at 91 and is pivotally connected at 92 to reciprocate the 50 control member 88. A spring 93 is connected to the bell crank and the control member to normally retain the control member in its innermost position. A wire connection 94 is secured at one end to the bell crank 88 and 55 at the other end to a treadle 95, which is

pivoted to the supporting frame to be conveniently manipulated by the foot of the operator of the typewriting machine.

When the treadle is pressed down the connection 94 will operate the bell crank and move the control member 88 outwardly, which will permit a coil spring 96 attached to the control member 85 and the clutch member 77 to automatically rotate the control member so that the semi-circular portion will extend 70 into the semi-circular aperture of the clutch member 76 and thereby provide a driving connection between the clutch members. When the treadle is released the control member will move into the path of the pin extension and will move it, as it engages therewith, so that the semi-circular portion of the pin will not engage in the apertures in the clutch member 76, and thus the driving connection will be broken. Thus by pressing 75 down on the treadle and then releasing it, the clutch members will be automatically engaged so that the element 77 and its shaft 78 will be driven one revolution, whereupon the pin 88 will be engaged by the control member and stop the rotation of the element 77 until the operator again presses the treadle down.

The mechanism for driving the primary and secondary feeding devices are so arranged that one revolution of the shaft 78 will operate them one complete movement to feed a work member from a source of supply into position on the platen for a typing operation.

It will thus be seen that the operator needs only to press on the treadle to cause the mechanism to automatically feed work members successively to the typewriter platen, and to automatically release after each actuation so that typing can be done thereon before the next work member is fed to the platen. The operator is saved the time and effort of operating the feeding mechanism manually, thus materially increasing the quantity of 100 work members which can be typed with this arrangement, over the heretofore manually-operated arrangement.

Various changes can be made in the details and arrangement of parts herein described and illustrated without departing from the spirit of my invention and the scope of what is claimed.

What I claim is:—

1. The combination of a typewriting machine, having a carriage and a platen; a work feeding device adapted to supply work members successively to said machine for a typing operation, said feeding device comprising an electric motor for operating said feeding device and for rotating the platen of said machine and reciprocating and rotating means connected with the typewriter carriage in order to feed a work member into a position with the platen for a typing operation and 120

125

130

to eject the preceding work member, speed reduction gearing driven by said motor; and a clutch connecting said gearing with said means, said clutch being manually operated to provide a driving connection and being 5 automatically released after each driving connection when said mechanism has been actuated a complete movement.

2. The combination of a typewriting machine, having a carriage and a platen; a work 10 feeding device adapted to supply work members successively to said machine, of an electrically driven motor for driving the feeding device, reciprocating and rotating means connected with the typewriter carriage and 15 with said feeding device so as to actuate the latter, said reciprocating means being arranged so as to effect the actuation of said feeding means during one stroke and the rotation of the typewriter platen during its 20 other stroke; a clutch interposed between the motor and the feeding device and means operable by the operator to set the reciprocating means in motion to feed the work to the typewriter platen.

25 In testimony whereof I affix my signature.
HARRY L. WOOD.
